UNITED STATES PATENT OFFICE

FRANK J. KRISTOFER, OF ST. PAUL, MINNESOTA, ASSIGNOR TO BROWN & BIGELOW, OF ST. PAUL, MINNESOTA, A CORPORATION OF MINNESOTA

PENCIL TIP

Application filed April 27, 1925. Serial No. 26,122.

My invention relates to pencils, as particularly designed to provide a tip for a pencil so as to form a finished writing end. This construction provides means so that if it is desired, precious metal can be attached over the tip to cover the same.

It is also a feature of my invention to provide a writing tip for the pencil which is provided with a shank attached to form the supporting end for the threaded tube of the pencil which forms a part of the propelling means. The tip thus supports the forward end of the threaded tube, holds it rigidly attached thereto and holds the tip in alignment with the barrel of the pencil.

My invention also includes a pencil wherein a portion of the propelling means is held removable from the rear end of the pencil barrel. The forward end is reduced and extends into the writing tip member so as to form a bearing for the forward end of the center tube of the propelling means to align the same with the tip and permit the lead in writing position in the pencil to be carried centrally with respect to the writing tip.

These features, together with other objects of my invention, will be more fully set forth in the following specification and claims.

In the drawings forming a part of my specification:

Figure 1 is a longitudinal cross section of a portion of my pencil illustrating my improvement and showing the operating center tube of the pencil in full.

Figure 2 illustrates the threaded tube and writing end removed from the pencil barrel in enlarged formation.

Figure 3 is an enlarged cross sectional view of the writing tip and forward end of the threaded tube.

Figure 4 illustrates an enlarged view of my writing tip in cross section.

Figure 5 is a cross section on the line 5—5 of Figure 1.

My pencil A is provided with a barrel 10 formed of any suitable material which is provided with an axially extending opening 11 and having the forward end 12 tapered to form a part of the writing end of the pencil.

The pencil A is provided with a tubular

threaded member 13 which is adapted to form a portion of the propelling means of my pencil A and which supports the writing tip 14.

The writing tip 14 is tapered in a manner to form a writing point 15 thereon and to provide a shoulder 16 spaced back of the point 15 which engages with the shoulder 17 formed on the barrel 10 at the forward portion 12 of the pencil barrel.

The tip 14 is formed with the shank 18 extending from the shoulder portion 16 which is of a diameter to be tightly and frictionally engaged in the unthreaded end 19 of the threaded member 13. This attaches the tip 14 rigidly to the threaded member to provide a means of supporting the writing tip 14 and holding the writing tip and the threaded member together.

The tip 14 is formed with an axial opening 20 which extends through the shank 18 and on the outer end of the shank 18 a counter bored portion 21 is provided. The threaded portion 13 and the tip 14 form a unit which is placed into the forward end of the barrel 10 under friction in a manner to hold the same firmly therein. If it is desired the rear edge 22 of the threaded member 13 may be pressed out on either side to form ears 23, as illustrated in Figures 1 and 5, to lock this unit, consisting of the threaded tip and unit 14, rigidly in the pencil barrel 10. It is not necessary to do this if the frictional engagement of the threaded tube with the barrel is sufficient to hold the same in place.

The writing tip unit and threaded member form one portion of the propelling means of the pencil A which is designed to be held in the pencil barrel 10 under ordinary conditions. If the unit is not locked by the ears 23 it may be removed as it is only held in the barrel under frictional tension.

The pencil A is provided with a center tube operating member B which forms the other part of the pencil A and which is removable, being held by the friction sleeve locking member 24 which is carried freely rotatable by the shoulder 25 formed on the member B. The member B is provided with an operating head 26 which is rigidly con-

ected to the enlarged portion 27 which is formed on the rear portion of the propelling member B and is adapted to form a lead magazine owing to its hollow tubular nature.

5 The head 26 is provided with an eraser 28 on the outer end of the same.

The member B is provided with a forward center tube portion 29 which is reduced in size as compared to the portion 27 and which 10 is adapted to extend through the threaded tube 13 with the forward end 30 extending into the opening 20 which forms a bearing for the forward end 30 of the center tube 29. The counter bored portion 21 of the tip 14 facilitates the end 30 freely entering the tip opening 20. The center tube portion 29 of the propelling member B of the pencil A is adapted to carry the writing lead 31. The writing lead 31 is carried by the pusher 32 which 20 slides back and forth in the tube 29 and is operated by engagement with the threaded tube 13.

The writing tip 14 may be provided with a swaged tapered end 33 to form the tip 15 of the pencil and in which instance the forward portion of the tip 14 is cut away at 34 and the tapered end 33 forms the forward end of the same. This tapered end 33 would only be used when it is desired to have the tip covered with the precious metal such as 30 silver, gold or other suitable material.

The end 33 is secured to the core of the tip 14 by rolling the rear edge 35 over the shoulder 16. In rolling the edge 35 over the shoulder 16 it is desirable to provide a square shoulder and thus the barrel 10, which is indicated in dotted outline in Figure 3, fits against the inturned edge 35 to form a smooth connection between the tip and the barrel 10.

40 In this manner I provide a pencil and construction which is very desirable, particularly where it is designed to use the barrel made of wood or non-metallic material, such as rubber, fiber or any other suitable non-metallic 45 material. This form of barrel forms a covering for the threaded tube 13 and the rear end of the operating member B of the pencil to provide a very attractive pencil, having a simple construction and of an inexpensive 50 nature. It is important that the tip 14 be held firmly and in my construction it is not necessary to solder the same onto the threaded tube 13 when it is desired to use a precious metal tip. The covering 33 is attached 55 in the manner described.

It is also an important feature of my invention to provide the bearing for the end 30 of the center tube of the operating propelling member B of the pencil. In this manner the 60 operating parts of the propelling means align with the opening 20 at the tip and permit the writing lead 31 to pass freely through the same.

In accordance with the patent statutes I 65 have described the principles of opera-

tion of my invention together with the illustrations which I now consider to be the best embodiment thereof, however, I desire to have it understood that the drawings are only illustrative and that the invention can 70 be carried out by other means and applied to uses other than those above set forth, within the scope of the following claims.

I claim:

1. A writing end for a pencil including a 75 tubular member, a tapered portion formed on the end of said member, an annular shoulder at the beginning of said tapered portion and a swaged tapered tip of precious metal adapted to be attached to said tapered portion by 80 rolling the inner edge of said swaged tapered tip over said shoulder to rigidly attach said swaged tapered tip to said portion.

2. A pencil tip including a tubular core member, one end of which forms a shank for 85 attachment with the body of the pencil and the other being formed with a tapered portion having an annular shoulder projecting about said shank and a precious metal swaged writing tip adapted to be rigidly attached to 90 said core member by rolling the inner edge of the same over said annular shoulder.

3. A pencil tip including a core member adapted to receive a thin shell-like facing tip 95 portion to rigidly support the same, the tip portion covering the core member, having a different outer face metal than the core member and an annular shoulder on said core member over which said facing engages.

4. A pencil including a writing tip having 100 a thin outer facing of precious metal, a barrel portion for supporting said tip of a non-metallic nature, a core extending from said barrel at the tip end to support said outer facing and an annular shoulder on said core 105 against which the front end of said barrel engages.

5. A pencil including a barrel of non-metallic substance, a propelling means extending in said barrel, a metallic tip for said barrel including a shell-like sleeve of a conical nature, a core member for supporting said tip rigidly with said barrel, an annular shoulder on said core and an annular edge on said sleeve adapted to project inwardly over said shoulder to rigidly support said tip.

FRANK J. KRISTOFEK.
